CLAIM

I claim the ornamental design for a cover panel of a box blank, as shown and described.

DESCRIPTION

FIG. 1 is a top perspective view of a cover panel of a box blank showing my new design, the broken line showing of the adjacent appended components is for illustrative purposes only and forms no part of the claimed design; FIG. 2 is a top plan view of the cover panel; the bottom view being identical.

FIG. 3 is a front elevation view of the cover panel; FIG. 4 is a right side elevation view of the cover panel; FIG. 5 is a left side elevation view of the cover panel; and, FIG. 6 is a rear elevation view of the cover panel.
